UNITED STATES PATENT OFFICE

2,482,926

DOOR LOCK

Joseph H. Milligan, Framingham, Mass.

Application November 2, 1946, Serial No. 707,437

6 Claims. (Cl. 70—217)

1

This invention relates to door locks of that type in which the lock mechanism is incorporated in one of the door knobs of the door, usually the outer knob.

One of the objects of the invention is to provide a novel door lock of this type in which the outer knob is normally locked from turning movement and is at the same time normally disconnected from the spindle by which the door latch is actuated, and which includes key-controlled means so constructed that when a key has been inserted into the key slot of the lock, the door knob can be unlocked and at the same time coupled to the spindle thus permitting the spindle to be turned from the unlocked outer knob for opening the door.

A further object of the invention is to provide a door lock of this type having novel means by which the normally locked outer knob can be unlocked and clutched to the spindle by manipulation of the inner knob.

A further object of the invention is to provide a novel door lock construction of this type in which the inner knob is movable axially between an outer and an inner position and in which when the inner knob is in one position, the outer knob will be operative to turn the spindle and open the door, while when the inner knob is in the other position, the outer knob will be rendered inoperative to turn the spindle.

Further objects of the invention are to provide improvements in door locks which will be more fully hereinafter set forth and pointed out in the appended claims.

In the drawings:

Fig. 1 is a view partly in section showing a door equipped with a door lock embodying my invention.

Fig. 2 is a section on the line 2—2 of Fig. 1.

Fig. 3 is a section on the line 3—3, Fig. 1.

Fig. 4 is a section similar to Fig. 2 but showing the outer knob unlocked and coupled to the spindle.

Fig. 5 is a perspective view of the barrel and key plug with which the outer knob is equipped.

Fig. 6 is a perspective view of the bearing member for the outer knob.

Fig. 7 is an exploded perspective view of the locking and clutching means.

Fig. 8 is a section on the line 8—8, Fig. 4.

Fig. 9 is a section on the line 9—9, Fig. 4.

Fig. 10 is a section on the line 10—10, Fig. 4.

Fig. 11 is a section on the line 11—11, Fig. 4.

Fig. 11a is a sectional view of the knob-supporting member.

2

Fig. 12 is a fragmentary sectional view showing a different embodiment of my invention showing the inner knob in its inner position.

Fig. 13 is a similar view showing the inner knob in its outer position.

Fig. 14 is a fragmentary sectional view taken at right angles to Fig. 12 and showing the operative connection between the inner knob and the spindle.

Fig. 15 is a similar view taken at right angles to Fig. 13.

Fig. 16 is a section on the line 16—16, Fig. 13.

Fig. 17 is a sectional view showing the rib 69.

Fig. 18 is a fragmentary perspective view of the means connecting the inner knob to the spindle.

Referring first to the construction shown in Figs. 1 to 11 of the drawings, 1 indicates a portion of a door which is equipped with my improved door lock, and 2 indicates a spring latch by which the door is latched to the keeper in the door frame. This spring latch may have any suitable or usual construction and it is of the type which is designed to be withdrawn from its engagement with the keeper for opening a door by the turning of a spindle 3, usually a flat-sided spindle, which extends through the door and forms part of the knob assembly, which also includes the inner knob 4 and the outer knob 5.

The inner knob 4 is rigidly secured to the spindle in some suitable way, while the outer knob is normally disconnected from the spindle and is normally locked against rotative movement.

In the construction herein shown, the inner knob 4 has a collar member 10 secured to its inner end by means of attaching screws 6. This collar 10 is provided with a square opening to receive the square spindle 3 as indicated in Fig. 11.

The inner knob 4 has a central bore in which 40 is received an internally screw-threaded sleeve 7 that is screw-threaded to the end of the spindle 3, the corners of the square spindle 3 being provided with screw-threads for this purpose. This sleeve 7 is shown as having a closed outer end

45 provided with a peripheral flange 8 which overlies the end of the inner knob 4 and is secured thereto by screws 9. Said inner knob is thus made fast to the spindle 3.

The outer knob 5 is mounted for turning movement on a knob-supporting member 11 that is secured to the outside of the door 1 by means of suitable screws 12. This knob-supporting member is provided with a central opening 13 through which the spindle 3 extends and is also formed

with a cylindrical flange 14 which forms a hub or bearing on which the outer knob is supported.

The outer knob 5 has a cup-shaped bearing member 15 secured to its inner end by means of screws 16, and the skirt or side wall portion 17 of the bearing member 15 encircles and has a supporting bearing on the flange 14. The bearing member 15 is held in place on the flange 14 by an annular member 18 which is secured to the door by screws 19 and the outer end portion of which encircles the skirt 17 of the bearing member 15, said member 18 being provided with an inwardly facing shoulder 20 which engages an outwardly facing shoulder 21 with which the skirt portion 17 of the bearing member is provided. These shoulders 20 and 21 hold the bearing member against the end of the flange 14 and prevent any axial movement of the outer knob 5.

The outer knob 5 is provided with a locking member, herein shown in the form of a disk 22 which is located within the flange 14 and is connected to the outer knob to turn therewith but which is capable of axial movement relative thereto. For this purpose the bearing member 15 is provided with one or more pins 23 which extend through openings 24 formed in the locking disk 22, and since the bearing member 15 is rigid with the outer knob 5, the engagement of the pins 23 in the openings 24 connect the locking member 22 to the outer knob for turning movement therewith but permit the desired axial movement thereof. The bearing flange 14 is provided on its inner face with a rib 25 that is provided with a notch 26, and the locking member 22 is formed on its peripheral edge with one or more locking projections 27 adapted to be received in the notch 26. In the construction herein shown, the rib 25 is provided with two notches 26 that are oppositely disposed, and the locking member 22 has two oppositely disposed locking projections 27.

Means are provided whereby normally the locking disk 22 will be positioned so that the locking projections 27 will occupy the notches 26 and thereby said locking disk is locked from turning movement, and since said locking disk is mounted on the pins 23, the outer knob will be locked from turning movement so long as the locking disk 22 is in a position in which the locking projections 27 occupy the notches 26.

Means are provided whereby normally the locking disk 22 will have this locked position. As herein shown, said disk 22 has rigid therewith a sleeve portion 28 which extends through the end of the bearing member 15 and into an axial chamber 29 with which the outer knob 5 is provided, the outer end of said sleeve member 28 being closed by a screw-threaded plug 30 which is screwed into the end of the sleeve portion 28. The plug 30 is formed with a head 31 somewhat larger in diameter than the sleeve 28, and a spring 32 encircles the sleeve 28 and is confined between the head 31 and a loose sleeve 33 which encircles the sleeve portion 28 and is located in the opening in the bearing member 15. The loose sleeve 33 has at its left-hand end a flange 33a (see Fig. 7) that normally engages the left-hand face of the bearing member 15 as clearly seen in Fig. 4, so that the tendency of the spring 32 is to apply to the head 31 of the screw 30 and thereby to the locking disk 22, a force urging said locking disk toward the left. The spring 32 is so tensioned that it normally holds the locking member 22 in the position shown in Fig. 1, wherein the projec-

tions 27 are located in the notches 26 of the rib 25.

The outer knob 5 is provided with key-controlled means by which the locking flange 22 can be moved axially to the right from the position shown in Fig. 2 into a position at one side of the rib 25 as seen in Fig. 4, in which position the locking projections 27 are freed from the notches 26 with the result that the outer knob 5 will be unlocked and can be turned.

The construction herein shown is also such that when the locking disk 22 is thus moved into unlocked position, it becomes coupled to the spindle 3 so that the spindle can be turned to open the door by the then unlocked outer knob.

The key-controlled means for thus unlocking the outer knob comprise a barrel element 34 located within the outer knob 5 and a key plug 35 mounted in the barrel element for turning movement, said key plug having the usual key slot 36 and being normally locked to the barrel element by the usual tumbler pins 37 and spring-pressed follower pins 38.

When a properly cut key 99 is introduced into the key slot 36 thereby to line up the tumbler pins, the key plug becomes unlocked and can be moved inwardly within the barrel 34 from its outer position shown in Figs. 1 and 2 to its inner position shown in Fig. 4. Such inward movement of the key plug 35 operates to shift the locking disk 22 from its locked position shown in Fig. 1 to its unlocked position shown in Fig. 4, in which the latter position it is coupled or clutched to the spindle 3 by means of the following mechanism.

Interposed between the key plug 35 and the plug 30 at the outer end of the sleeve 28 is a disk 39 having a stem 40 which extends through an opening in the plug 30. This disk element is acted on by a spring 41 which bears at one end against the bearing member 15 and at the other end against said disk element 39, said spring holding said disk element yieldingly against the end of the key plug and applying sufficient tension thereto to prevent the follower pins from binding when the key is inserted into the key slot.

When the key plug is moved inwardly into the position shown in Fig. 4, it forces the disk element 39 against the plug 30 and thereby moves the sleeve portion 28 and the locked disk 22 inwardly, such movement carrying the locking projections 27 out from the notches 26 of the rib 25 thereby unlocking the outer knob. During such inward movement of the sleeve 28 and disk 22, the spring 32 will be compressed since one end thereof bears against the head 31 of the plug 30 which is screwed into the sleeve 28 and the other end bears against the flange 33a of the sleeve 33, which flange engages the bearing member 15.

As stated above, this inward movement of the locking disk 22 clutches or couples it to the spindle 3. For this purpose, the spindle 3 has at its outer end a coupling flange 42 provided with openings 43 adapted to receive clutching or coupling pins 44 with which the locking disk 22 is provided.

When the locking disk 22 is in its locked position shown in Fig. 1, the pins 44 will be disconnected from the coupling flange 42, but the inward axial movement of the locking member 22 necessary to unlock it from the rib 25 will bring the pins 44 into coupling engagement with the openings 43 in the coupling flange 42.

The door can thus be unlocked by inserting a

proper key 99 into the key slot 36 to unlock the key plug and then by pushing the key and key plug inwardly into the position shown in Fig. 4, with the result that the locking member 22 is released from the locking rib 25 and coupled to the spindle 3. The turning of the unlocked outer knob 5 will thus cause the spindle 3 to turn thereby withdrawing the latch 2 from the keeper in the door frame.

Means are provided for holding the key plug in its inner position shown in Fig. 3 while the outer knob 5 is being manipulated. For this purpose the key plug is provided with a pin 45 which is normally received in a groove 46 with which the barrel element 34 is provided. When the key plug is moved inwardly into the position shown in Fig. 2 for unlocking the outer knob, the pin 45 is carried out of the slot 46 into a recess 47 formed in the inner end of the barrel 34. By turning the key 99 and the key plug slightly after the pin 45 has been moved out of the slot 46 as shown in Fig. 5, the pin 45 will be moved against the inner wall of the recess 47 at one side of the slot thereby holding the plug in its inward position and holding the locking disk 22 in its unlocked position coupled to the spindle.

So long as the key remains in the key slot as shown in Fig. 5, the outer knob will remain unlocked and coupled to the spindle and will thus remain operative for opening the door.

To withdraw the key, it is necessary to turn the key plug to bring the pin 45 into register with the slot 46 and when this has been done, the plug may be moved outwardly into the position shown in Fig. 2 by pulling on the key 99, such movement of the plug being assisted by the springs 41 and 42. When the key plug is back in the outer position shown in Figs. 1 and 2, the tumbler pins and follower pins 37 and 38 automatically lock the plug.

As stated above, the spring 32 is so tensioned that when the key plug 35 is restored to its normal outer position shown in Fig. 2, said spring acting on the flange 33a will return the disk 22 to its central locked position shown in Fig. 1.

My improved lock is also constructed so that the outer knob can be unlocked and coupled to the spindle by proper manipulation of the inner knob 4 and without the use of a key. The inner knob 4 and the spindle 3 are capable of axial movement from an outer position shown in Fig. 1 to an inner position shown in Fig. 2. When the inner knob and the spindle 3 are thus moved into their inner positions, the coupling flange 42 on the spindle is brought into coupling engagement with the pins 44 of the locking member and the engagement of the coupling flange 42 with the locking flange 22 pushes the latter outwardly a sufficient distance to withdraw the locking projections 27 from the notches 26 in the rib 25 and to locate the locking disk 22 on the outside of the rib 25 as shown in Fig. 2. The outer knob is thereby unlocked so that it can be turned and it is also coupled to the spindle so that the door can be unlocked and opened from the outer knob without the use of a key.

Attached to the inside of the door by screws 48 is a rose element 49 which encircles the collar 40 at the inner end of the inner knob 4. This rose element is provided with two annular grooves 50 and 51 which form between them a rib 52. Said rib is formed with one or more notches or openings 53 and the collar 40 is provided with a projection 54 adapted to operate in either one of the grooves 50 and 51.

Normally the inner knob 4 and the spindle are

positioned so that the projection 54 is in the outer groove 50 thereby placing the coupling flange 42 on the spindle in the position shown in Figs. 1 and 4.

When it is desired to unlock the outer knob from the inner knob, the latter is turned to bring the projection 54 in line with the notch 53 and then the inner knob with its spindle is pushed inwardly into its inner position shown in Fig. 2 thereby to bring the projection 54 into registration with the inner groove 51. This inward movement of the knob and the spindle serves to couple the coupling flange 42 to the locking member 22 and also serves to move the locking member 22 outwardly into a position on the outer side of the rib 25 thereby unlocking said outer knob. By turning the inner knob slightly, the projection 54 is carried out of registration with the slot 53 and the inner knob will then be held in its inner position by engagement with the rib 54. When the parts have been thus adjusted, then the outer knob is unlocked and coupled to the spindle so that a person may open the door simply by turning the outer knob and without the use of a key. This makes it possible for a person within a room to set the lock so that anyone can enter the room without having to use a key for this purpose.

In the door lock construction shown in Figs. 1 to 4, the spindle is free at all times to be turned by the inner knob and can be turned by the outer knob when the latter is unlocked and clutched to the spindle either by the key-controlled means as shown in Fig. 4, or by shifting the inner knob inwardly into the position shown in Fig. 2.

In Figs. 12 to 16 there is shown a different embodiment of the invention in which the spindle is normally free to be turned by the inner knob but is locked against turning movement by shifting the inner knob in an axial direction, thereby making it impossible to open the door from the outer knob even when the outer knob is unlocked by means of the key.

In the construction shown in Figs. 12 to 16, the spindle is indicated at 3a and it is adapted to be clutched to the outer knob when the latter is unlocked by the means illustrated in Figs. 1 to 5.

In Figs. 12 to 16 the inner knob is shown at 4a and it is formed with a hub portion 60 within which is received a sleeve 61 that is provided with a square opening 62 that fits the square spindle 3a so that the sleeve 61 and the spindle must always rotate as a unit. The sleeve 61 is formed at its inner end with a flange 63 which normally engages the inner end of the hub 60 of the inner knob. The flange 63 is provided with an outwardly extending locking projection 64 which is normally received in a groove 65 formed on the inside of the rose 66.

The hub 60 is also provided with an outwardly extending projection 67 which when the parts are in normal position shown in Fig. 12 registers with the projection 64 and is also located in the groove 65.

The rose 66 is provided with an interior rib 69 which is formed with a passageway 70 of a size to receive the projections 64 and 67.

The inner knob 4a is mounted for axial movement from the normal position shown in Fig. 12 to a spindle-locking position shown in Fig. 13, and means are provided whereby when the knob is moved from its normal position to its spindle-locking position, the locking projection 64 on the flange 63 is moved into the passageway 70 in the rib 69 while the projection 67 on the hub 60 is

75 rib 69 while the projection 67 on the hub 60 is

carried clear through said passageway into a position outside of the rib 69.

When the parts are in this position, the sleeve 61 will be locked from turning movement by reason of the fact that the projection 64 thereon occupies the passageway 70, and thereby the spindle 3a will be locked from turning movement. This locking of the spindle will be effective even though the outer knob is unlocked by the key and has been clutched to the spindle as shown in Fig. 4. The construction shown in Figs. 12 to 18 therefore provides means by which a person on the inside of the room, may, by manipulating the inner knob, lock the spindle from turning movement and thereby prevent anyone from opening the door by means of the outer knob even though such person has the proper key with which to unlock the outer knob.

The spindle 3a is shown as provided on its end with a head 71 which is received in an axial recess 72 with which the inner knob 4a is provided. A spring 73 encircles the spindle and is confined between the head 71 and the inner end of the recess 72, said spring normally holding the parts in the relative position shown in Fig. 12.

The sleeve 61 is provided with a pin or projection 74 and the hub 60 is provided with a slot 75 and with a notch 76 in the outer wall of the slot.

When the parts are in normal position shown in Figs. 12 and 14, the pin 74 occupies the notch 76 and thus the inner knob is locked to the sleeve so that turning movement of the said knob will turn the sleeve and thus turn the spindle, which at such time is unlocked by reason of the fact that both the projection 64 on the sleeve and the projection 67 on the hub 60 of the outer knob are occupying the inner groove 65.

The inner knob is provided with a groove 77 in which is located a thrust pin 78, said pin being confined between the outer end of the sleeve 61 and the head 71 on the spindle. In this embodiment the spindle is held from axial movement toward the right, and, as a result, when the inner knob is moved axially of the spindle from its normal position shown in Fig. 12 into its spindle-locking position shown in Fig. 13, the sleeve will move with the knob outwardly until the outer end of the pin 78 is brought up against the head 71 on the spindle. This movement of the knob and sleeve is sufficient to carry the projection 64 on the sleeve into the passageway 70 of the rib 69. When the pin 78 has thus been moved against the head 71 of the spindle, then said pin can move no further and consequently the sleeve 61 is prevented from further axial movement.

A continued further axial movement of the inner knob 3a, however, carries the pin 74 out of the notch 76 into the slot 75, this movement being sufficient to carry the projection 67 on the hub 60 clear through the passageway 70 and outside of the rib 69. The inner knob may then be turned slightly to carry the projection 67 in front of the rib 69 thereby locking the inner knob in its spindle-locking position as seen in Fig. 15. The extent of the turning movement of the inner knob for this purpose depends upon the length of the slot 75.

I claim:

1. A door lock comprising a latch-releasing spindle extending through the door, an inner knob fast on said spindle, a knob-supporting member fixedly secured to the outer side of the door, an outer knob rotatably mounted on the knob supporting member, a knob-locking mem-

ber movable axially relative to the outer knob but connected thereto to rotate therewith, said knob-locking member and knob-supporting member having cooperating means locking the knob-locking member and thus the outer knob from turning movement when said knob-locking member is in one position, said spindle and inner knob being movable axially from an outer to an inner position, and means rendered operative by the movement of said inner knob and spindle into their inner positions to shift the knob-locking member axially from its locked position to an unlocked position and to clutch said knob-locking member to the spindle.

15 2. A door lock comprising a latch-releasing spindle extending through the door, an inner knob fast on said spindle, a knob-supporting member fixedly secured to the outer side of the door, an outer knob rotatably mounted on the knob-supporting member, a knob-locking member movable axially relative to the outer knob but connected thereto to rotate therewith, said knob-locking member and knob-supporting member having cooperating means locking the knob-locking member and thus the outer knob from turning movement when said knob-locking member is in one position, said spindle and inner knob being movable axially from an outer to an inner position, and means rendered operative by the movement of said inner knob and spindle into their inner positions to shift the knob-locking member axially from its locked position to an unlocked position and to clutch said knob-locking member to the spindle, and means for retaining the inner knob and spindle in their inward position while permitting turning movement thereof.

30 3. A door lock comprising a latch-releasing spindle extending through the door, an inner knob mounted on the inner end of said spindle, a knob-supporting member fixedly secured to the outer side of the door, an outer knob rotatably mounted on said knob-supporting member, a knob-locking member connected to the outer knob to rotate therewith and movable axially in either direction from a central locked position to an unlocked position, means for locking said knob-locking member from turning movement when in its central position, key-controlled means to move the knob-locking member axially in one direction from its central locked position to an unlocked position and to clutch said knob-locking member to the spindle, thereby rendering the outer knob operative to turn said spindle, said inner knob and spindle being movable axially, and means rendered operative by an axial movement of the spindle and inner knob to move the knob-locking member axially in the other direction from its central locked position to an unlocked position and to clutch said knob-locking member to the spindle thereby to unlock the outer knob and render it operative to open the door.

35 4. A door lock comprising a latch-releasing spindle extending through the door, an inner knob mounted on the inner end of said spindle, a knob-supporting member fixedly secured to the outer side of the door, an outer knob rotatably mounted on the knob-supporting member, a knob-locking member connected to the outer knob to rotate therewith and movable axially in either direction from a central locked position to an unlocked position, said knob-supporting member and knob-locking member having cooperating means for locking the knob-locking member from turning movement when it is in

its central position, key-controlled means to move the knob-locking member axially in one direction from its central locked position to an unlocked position and to clutch it to the spindle thereby rendering the outer knob operative to turn said spindle, said inner knob and spindle being movable axially, and means rendered operative by an axial movement of said spindle and inner knob to move the knob-locking member axially in the other direction from its central locked position to an unlocked position and to clutch said knob-locking member to the spindle thereby to unlock the outer knob and render it operative to open the door.

5. A door lock comprising a latch-releasing spindle extending through the door, an inner knob mounted on the inner end of the spindle, a knob-supporting member secured to the outer side of the door and presenting a cylindrical flange co-axial with the spindle, an outer knob mounted for turning movement on said cylindrical flange, a knob-locking disk located within said cylindrical flange and movable axially in either direction from a central locking position, means connecting said disk to the outer knob for turning movement therewith, said locking disk and cylindrical flange having cooperating means to lock the disk and therefore the outer knob from turning movement when said disk is in its central position, means normally holding said disk in such central position, said disk being free for turning movement when moved either inwardly or outwardly from said central position, key - actuated means associated with said outer knob and moving said knob-locking disk from its central locked position to its inner unlocked position, means for clutching said disk to the spindle when in such inner unlocked position, said inner knob and spindle being movable

axially and said spindle having means associated therewith to move the knob-locking disk into its outer unlocked position and to clutch said disk to the spindle when the inner knob is moved axially.

6. A door lock comprising a latch-releasing spindle adapted to extend through a door, an inner knob mounted on said spindle, an outer knob mounted on the outside of the door, a knob-locking member movable axially relative to the outer knob between a locking position and an unlocked position but connected to the outer knob to rotate therewith, means cooperating with said knob-locking member to lock it from turning movement when it is in the locking position, said knob-locking member being normally disconnected from the spindle, said spindle being movable bodily in an axial direction, and means rendered operative by the bodily axial movement of the spindle to move the knob-locking member axially from its locking position to its unlocking position and simultaneously to clutch said knob-locking member to the spindle.
